(57) **CLAIM**

The ornamental design for a pump head, substantially as shown and described.

DESCRIPTION

FIG. 1 is a perspective view of a pump head; FIG. 2 is a top view of the pump head illustrated in FIG. 1; FIG. 3 is a side view of the pump head illustrated in FIG. 1; FIG. 4 is a side view of the pump head illustrated in FIG. 1; FIG. 5 is a bottom view of the pump head illustrated in FIG. 1; FIG. 6 is a rear view of the pump head illustrated in FIG. 1; FIG. 7 is a front view of the pump head illustrated in FIG. 1; and, FIG. 8 is a perspective view of a pump head illustrated in FIGS. 1 through 7 attached to a bottle with a closure. In FIGS. 1 through 7, the broken lines show portions of the pump head that form no part of the claim; in FIG. 8, the broken lines also depict a bottle and closure that form no part of the claimed design.

1 Claim, 4 Drawing Sheets
